NORMAN P. HARSHBERGER, OF PASADENA, CALIFORNIA, AND RUSSELL P. HARSHBERGER, OF SOUTH BEND, INDIANA; SAID RUSSELL P. HARSHBERGER ASSIGNEE TO SAID NORMAN P. HARSHBERGER

COMPOSITION SHINGLE

Application filed April 19, 1926. Serial No. 102,879.

This invention relates to composition shingles and particularly to shingles consisting of individual shingles and a very pleasing appearance when laid on the roof, and also 5 to provide means for locking down the exposed lap portions of the shingle, so as to overcome the tendency of these portions to warp. A particular purpose of the invention is to provide a method for producing in 10 an efficient and economical manner shingles of this nature.

Of the accompanying drawings Fig. 1 is a plan view of a sheet of shingle material showing how the individual strip shingles 15 are cut from the sheet; Fig. 2 is a plan view of a portion of a plurality of shingles embodying the features of our invention as they appear when laid on a roof; and Fig. 3 is an enlarged plan view of an individual unit.

20 The shingle which we have invented may be called an octagon strip shingle, as the figures which are produced by laying the shingles on the roof are octagon shaped, although the shape of the shingles and particularly 25 the figures produced may be varied more or less without departing from the spirit of my invention. In this particular instance, however, the shapes produced are those of equi- 30 angular and equilateral octagons. As is indicated by Fig. 1, the method by which these shingles are cut out from the sheets consists in cutting zigzag lines through the central portion of the sheet, the lines forming three 35 sides of the octagon portions of the figures when laid. The projections in one shingle are formed by cutting corresponding recesses in the adjacent shingle, these recesses and 40 projections comprising three sides of the octagon. The sheet is then cut transversely to form the individual units, the transverse cuts also being zigzag or broken lines, as indicated.

The shingle comprises a body portion 5 having a straight edge 6, and straight ends 45 7 and 8, preferably at right angles to the edge 6, and on the opposite edge having octagon portions 9 and 10 projecting from the shingle. There is also on this edge a projection 11 which is one-half the length of the projections 9 and 10, and has one-half of an octa-

gon side 12 and 13 at each of its ends, these sides being parallel and forming with an adjacent edge an angle of 135°. A slot or slit 14 is formed in the projection 11 at the inner corner thereof, the slot being at an angle of 55 substantially 90° with the adjacent edge 12. At the other end of the shingle a tongue 15 is formed and between it and the body of the shingle is a slit 16. The units are arranged to be formed in strips, the adjacent ends being locked together by means 60 of the tongues 15, and the slots 14 and 16. As indicated, the tongue 15 passes under the lower edge of the adjacent shingle with the slits coacting and the inner ends of the 65 slits coinciding. When thus laid the projections of one shingle 9 covers the projection 11 of the adjacent shingle and a continuous row of interlocked units presents a series of 70 projections similar in shape to 9 and 10.

When the strips thus formed are laid on the roof one strip may lap as much as may be desired on the underlying strip. We prefer to have the distance between the outer end 75 of the projection 10 of one strip from the inner end of the recess 16 of the underlying strip equal to the length of the outer edge 17 of the projections, and also to have the two 80 projections opposite a recess. This gives the appearance on the roof of an equilateral octagon formed by the edges of the registering projection and recesses. When thus formed a very pleasing appearance is given to the 85 roof and the ends of the shingles lap sufficiently to prevent any leakage at the ends, and by inserting nails at the points 20 and 21 the shingles are firmly fastened to the roof, 90 no nail heads are exposed, and the possibility of the exposed portions warping upwardly is substantially eliminated. As will 95 be seen the nails 20 are covered by the projections 9 of the adjacent overlying shingles.

We claim as our invention:

1. A combination strip shingle comprising 95 a plurality of units placed in a row with their respective adjacent ends lapping, and means for locking together such respective ends, each of said means comprising a tongue projecting longitudinally from one of the adjacent ends, said end having a slit part way 100

across the inner end of said tongue, the other adjacent end having a slit extending inwardly from the side edge and spaced a material distance from the end, but slanting towards said end, said tongue being positioned under said side edge with the slits interlocking, one edge of the combination shingle comprising a series of projections of similar shape extending uniformly all along the edge, each of said slanting slits extending inwardly from one of said projections intermediate of its length.

5. A combination strip shingle comprising a plurality of units placed in a row with their respective adjacent ends lapping, and means for locking together such respective ends, each of said means comprising a tongue projecting longitudinally from one of the adjacent ends, said end having a slit part way across the inner end of said tongue, the other adjacent end having a slit extending inwardly from the side edge and spaced a material distance from the end, said tongue being positioned under said side edge with the slits interlocking, one edge of the combination shingle having a series of projections of similar shape extending uniformly all along the edge, the two interlocking slits being positioned in overlapping projections.

10. 2. A combination strip shingle comprising a plurality of units placed in a row with their respective adjacent ends lapping, the edge of said units which is adapted to be exposed having a plurality of projections of similar shape, each projection adjacent the lapping ends of two units being formed by a complete projection of one unit having locking means in connection therewith and by a partial projection of the other unit having locking means which cooperates with the locking means of the complete projection, said partial projection having its inner side cut to register with the outer side of the complete projection with which it interlocks.

15. 3. Strip shingles comprising a plurality of units placed in a row with their adjacent ends lapping, the edge of said units which is adapted to be exposed having a plurality of projections of similar shape, each projection adjacent the lapping ends of two units being formed by a projection of one unit having locking means in connection therewith and by a projection of another unit having locking means which cooperates with the locking means of the other projection, said two projections having registering sides.

40. In testimony whereof we hereunto set our hands.

NORMAN P. HARSHBERGER.
